[57] CLAIM

The ornamental design for a wheel assembly for luggage, as shown and described.

DESCRIPTION

FIG. 1 is a bottom plan view of a wheel assembly for luggage showing my new design, the top plan view is plain and unornamented;

FIG. 2 is a side elevational view thereof, the opposite side is similar, except for a difference in height as best illustrated by FIG. 3;

FIG. 3 is an end elevational view thereof, the opposite end is a mirror image; and,

FIG. 4 is a partial exploded perspective view broken away for purposes of illustration.

FIG. 1

FIG. 2

FIG. 3
